(57) **CLAIM**

The ornamental design for a tee fitting of a tubing ring, as shown and described.

DESCRIPTION

FIG. 1 is a perspective view of a tee fitting of a tubing ring according to our new design, shown in a state of use in its intended environment;

FIG. 2 is an enlarged view of portion 2 in FIG. 1;

FIG. 3 is perspective view of the tee fitting of a tubing ring of FIG. 1;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines illustrate portions of the tee fitting of a tubing ring and form no part of the claimed design.

The large dash broken lines encircling portions of the tee fitting of a tubing ring in FIG. 1 and illustrated in enlarged views in FIG. 2 form no part of the claimed design.

1 Claim, 6 Drawing Sheets
